UNITED STATES PATENT OFFICE.

ARTHUR C. EASTWOOD, OF CLEVELAND, OHIO, ASSIGNOR TO THE ELECTRIC CONTROLLER AND MANUFACTURING COMPANY, OF CLEVELAND, OHIO, A CORPORATION OF OHIO.

SOLENOID WITH SHUNT.

1,004,860.

Specification of Letter's Patent.

Patented Oct. 3, 1911.

Application filed June 7, 1910. Serial No. 565,589.

To all whom it may concern:

Be it known that I, ARTHUR C. EASTWOOD, a citizen of the United States, residing at Cleveland, in the county of Cuyahoga and State of Ohio, have invented new and useful Improvements in Solenoids with Shunts, of which the following is a specification.

My invention relates to improvements in electric circuits containing solenoids which are connected in series with a motor or whose energizing winding carries a large current. Where a solenoid brake-winding is in series with a motor circuit, it has heretofore been necessary to provide a different size of wire for the solenoid-winding for each size of motor.

It is the object of my invention to provide for using one size of wire in solenoid-windings to cover a large range of motors or their equivalents.

Referring to the accompanying drawing which illustrates one of the many forms which my invention may assume, Figure 1 is a central vertical section of a brake-solenoid provided with my improvement; and Fig. 2, a diagram of a motor circuit including a solenoid winding with its brake-connections and shunt circuit.

On the drawing, C is the frame of the solenoid and contains the winding B, which is provided with a vertical axial opening for the reciprocation of the plunger A. The plunger may be connected to various mechanisms, but I have shown it connected to the arm of the friction brake N of well-known construction. The frame C and the winding are covered by the cap-plate or cover D, having in line with the plunger A an opening which permits the plunger, on energization of the winding B, to rise and engage the switch arm E and force it into engagement with the fixed contact F, which closes a shunt path through the resistance element or strip H and around the said winding B. The plunger works in the brass tube K, on which the winding B is wound.

The fixed contact F, the support for the switch arm or movable contact E, and the posts h for the resistance element H are supported by the solenoid but separated therefrom by the insulation pieces J. The re-

sistance element is secured to the posts h by the screws h'. A number of these resistance elements are provided, and for a small 55 motor one may be used in the shunt circuit, and for larger motors other strips may be placed one on another and all secured by the screws h' or in any other desired manner. The entire range of solenoids required 60 in connection with motors of 10 to 100 horse-power, for example, might be covered by two standard solenoids, one having its winding serving, for example, from 10 to 50 horse-power, and the other from 60 to 100 65 horse-power. With the 10 horse-power size, the shunt would not be necessary. With a 15 horse-power size a single strip H would be used; with a 20 horse-power size, two strips H would be used and so on. When 70 the larger solenoid is used with larger motors, the strips H would be added in a similar manner. Thus, it is possible to manufacture coils and other parts of the solenoids in large quantities, and keep them 75 in stock, as the varying number of strips H on the shunt is the only alteration required to adapt them to different horse-powers. My invention is advantageous from an operating standpoint, owing to the small number of repair parts required in large installations covering a number of motors of different horse-power.

In the diagrammatic view, Fig. 2, the current passes from the positive side of 85 the line through the controller G, the armature L, the field M, and the solenoid winding B to the negative side of the line. The motor-current passing through the winding B, causes the plunger A to rise and release 90 the friction brake N, and at the same time to close the contacts E and F, whereupon a portion of the motor current is diverted from the windings B and passes to the negative side of the line through the resistance 95 strip H and the contacts E and F.

My invention takes into account the fact that it requires a larger number of ampere turns to cause the solenoid-plunger to act at the beginning of a stroke than it requires to hold the plunger after it has acted, when the air-gap has been cut down to practically nothing. The size of the wire in the solenoid winding need be only large

enough to carry the amount of current required to actuate the plunger and hold it after it has reached the end of its stroke.

I claim—

- 5 In a motor control system, a motor, a circuit for the same, a brake winding in series with the motor, a shunt around the winding, a switch to close the shunt when current is flowing through the motor and the said
- 10 winding, a mechanical brake connected to the solenoid and made ineffective while cur-

rent is flowing in the winding, and means for making the brake effective when current ceases to flow through the motor and the winding.

15

Signed at Cleveland, Ohio, this 2nd day of June, A. D. 1910.

ARTHUR C. EASTWOOD.
